United States Patent Office

Des. 188,664
Patented Aug. 23, 1960

188,664

BADGE

Claire A. Chapin, R.F.D. 3, Box 384, Pottsville, Pa.

Filed Apr. 3, 1959, Ser. No. 55,339

Term of patent 7 years

(Cl. D29—2)

FIG. 1

Fig. 2 is an end elevational view thereof.

The dominant features of my design are shown in full lines.

I claim:

The ornamental design for a badge, substantially as shown and described.
